UNITED STATES PATENT OFFICE

2,066,845

KNITTING MACHINE

Harry McAdams, Reading, Pa., assignor to Nolde and Horst Company, Reading, Pa., a corporation

Application June 28, 1932, Serial No. 619,779

8 Claims. (Cl. 66—135)

This invention relates to improvements in knitting machines.

The primary object of this invention is the provision of an improved knitting machine which will produce knitted fabric having incorporated plated stripes and designs.

A further object of this invention is the provision of an improved knitting machine which will produce knitted fabric with incorporated plated designs of multi-colored yarns similar to the machine set forth in my co-pending application, Serial Number 591,689, filed February 8, 1932, but which is relatively simpler than the machine of said application from the standpoint of structure, operation, and accessibility of fabric and parts.

A further object of this invention is the provision of an improved knitting machine whereon knitted fabric, such as hosiery, may be knitted with incorporated plated designs of multi-colored yarn wherein colored plating yarns are knitted in the same courses as other contrasting-colored plating yarns, using the needle wrapping method.

Other objects and advantages of this invention will be apparent during the course of the following detailed description.

In the accompanying drawings, forming a part of this specification, and wherein similar reference characters designate corresponding parts throughout the several views,

Figure 1 is a front elevation of the improved knitting machine.

Figure 2 is a vertical sectional view taken through the upper portion of the knitting machine showing more particularly the rotary needle cylinder, bobbin stand, and plating yarn member actuating mechanism.

Figure 3 is a vertical sectional view taken through the bobbin stand showing more particularly the yarn feeding members and the mounting of the bobbin stand upon the conventional latch ring.

Figure 4 is a sectional view taken substantially on the line 4—4 of Figure 11 through different yarn feeding members than those shown in section in Figure 3.

Figure 5 is a fragmentary perspective view showing the relation of yarn feed arm or member and plating yarn restraining wire with respect to the needle of the knitting yarn which is elevated to receive the yarn in needle wrapped relation thereto.

Figure 6 is a vertical sectional view taken through the knitting machine cylinder, showing

more particularly the yarn guide wire and its actuating means for restraining the yarn in order that the elevated needle of the cylinder will receive the same; the view also showing needle actuating cam means for selective elevation of 5 the needles into plating yarn receiving position.

Figure 7 is a sectional view taken substantially on the line 7—7 of Figure 3 through the base of the slidably reciprocatory yarn feed members or arms.

Figure 8 is a transverse sectional view taken substantially on the line 8—8 of Figure 7.

Figure 9 is a plan view, partly in section, of the lower portion of the bobbin stand showing its relative mounting upon the knitting machine 15 latch ring and associated parts; the view being taken substantially on the line 9—9 of Figure 3.

Figure 10 is a sectional view taken substantially on the line 10—10 of Figure 3.

Figure 11 is a sectional view similar to Figure 20 10, but showing the yarn feed arm actuating cam in yarn feed arm extending position.

Figure 12 is a bottom plan view of the base portion of the bobbin stand upon which the yarn feed arms are slidably mounted.

Figure 13 is a sectional view taken through the improved knitting machine showing more particularly the yarn feed arm actuating means and a pattern control drum actuating mechanism.

Figure 14 is a fragmentary developed view 30 showing the lug arrangement upon the pattern cam control drum for the actuating of cams in order to manipulate in a selective manner the needles of the cylinder for production of the wrapped needle plated designs shown in Figure 35 18.

Figure 15 is a horizontal sectional view taken substantially on the line 15—15 of Figure 3 showing the upper set of plating yarn feed arms and the actuating cam thereof in an active position.

Figure 16 is a sectional view similar to Figure 15 but showing the actuating cam in position for needle yarn feed positioning of the yarn feed arms of the upper set.

Figure 17 is a view on a developed plane of 45 the needle set and cooperating series of jacks in associated relation with a series of yarn guide or controlling arms or members, and the jack, needle, and yarn feed arm operating cams for the knitting of the fabric shown in Figure 18. 50

Figure 18 is a fragmentary enlarged view showing by way of example one type of plated design which may be knitted in the fabric by the improved machine shown in Figures 1 to 17 inclusive.

Figure 19 is a sectional view taken substantially on the line 19—19 of Figure 7, and showing more particularly the base construction of the rotary part of the needle stand upon which the 5 yarn feed arms are slidably mounted.

Figure 20 is a fragmentary view on a developed plane of the needle set and cooperating series of jacks in associated relation with a 10 series of yarn guide arms, and the jack, needle 15 and yarn feed arm operating cams for the knitting of the plated fabric shown in Figure 21.

Figure 21 is a type of knitted fabric wherein the plated design or striping is produced in the fabric without knitting different plating colors 15 within the same courses, and thereby enabling a simpler arrangement of actuating cams and jacks than is necessary for the knitting of the "color within color" plated designs such as shown in Figure 18.

20 In the drawings, wherein for the purpose of illustration are shown preferred and modified forms of the invention, the letter A may generally designate the improved knitting machine, which may include a frame B, cylinder C, means 25 D for operating the cylinder and driving the machine, a set of needles E, a set of jacks F to actuate the needles E, means G to actuate the jacks, a yarn controlling device H for wrapping the yarns upon the needles of the machine, and 30 means K for actuating the yarn guide arms or members of the means H. By way of example fabrics L and M are shown respectively in Figures 18 and 21, but it is to be understood that a wide variety of designs and plated patterns or 35 stripings may be produced in knitted fabrics upon the improved machine by utilizing a re-arrangement of jack butts thereon, and actuating cams therefor, as will be apparent to those skilled in the art upon reading the disclosure 40 herein set forth.

The knitting machine is of the Banner type generally disclosed in U. S. Patent 933,443, and its operation includes many of the characteristics of the plating design knitting machine set 45 forth in my co-pending application Serial No. 591,689 above mentioned, but is relatively simpler in operation and structural assemblage. The frame B is provided with a supporting bed 20 upon which the cylinder C is rotatably mounted, 50 as shown in Figure 2. The cylinder rotating and oscillating means is of the usual arrangement for hosiery knitting machines of this type. The cylinder C is driven off the main shaft 21, shown in Figure 13, by the usual bevel gear arrangement 55 shown at 22 in Figure 2 of the drawings.

55 The cylinder C may be of the special construction described in my co-pending application above referred to. It is provided with needle grooves 26 therein, which are relatively deep 60 in order to adapt the cylinder for the reverse plating of body knitting yarns as set forth in my co-pending application Serial Number 586,-635, filed January 14, 1932, although in the example shown herein only one main yarn is used 65 to produce the knitting of the main web of the fabric. The needles 32 of the set E are of the latch type, substantially half of them having long butts 40 and the remainder having shorter butts 41; the former being designated in full 70 black in Figures 17 and 20 of the drawings. The jacks 31 of the set F are of the construction described in my co-pending application Serial No. 591,689 above mentioned, in that each of them is provided with a body having a plurality 75 of frangible butts in spaced relation at the lower

end thereof before alteration, to suit the pattern being knitted. Preferably six of these butts are provided on each jack, and any or all of them may be snapped off at the juncture thereof with the shank of the jack, or at any place 5 along the length of the butt either to remove the same or make the same into a butt of desired length. Thus, each jack may be provided with any butt arrangement desired in order to selectively control the actuation of predetermined 10 needles for receiving the plating yarns, as will be subsequently described.

The jack actuating means G preferably includes a pair of supporting blocks 50 and 51, shown in Figure 1 of the drawings, and in detail shown in Figure 6 of the drawings. Each of these blocks is provided with a vertical series of horizontal slots therethrough preferably radial to the cylinder C. They are attached upon the bed 20 of the machine, and the slots 52 thereof 20 slidably receive flat horizontally elongated and positioned cams which are slidable into and out of butt engaging and jack actuating relation. Any number of slots may be provided in the blocks 50 and 51. For the knitting of the plated 25 pattern shown in Figure 18 the block 50 is slidably provided with cams 53, 54, 55, 56, and 57, as shown in Figure 6 of the drawings; the cam 57 being lowermost. The block 51 is provided with three cams 58, 59, and 60, best shown in 30 Figure 17 of the drawings. These cams 53 to 60 inclusive are provided with angularly inclined cam heads positioned at different levels for engaging butts of the jacks which approach that level so as to elevate the jacks having butts 35 at that level in order to place the hook ends of the needles in position so that the plating yarn feeds of the bobbin stand H may wrap particular plating yarns thereon. The cams 53 to 60 inclusive are so positioned that they will 40 only actuate upon the long butts of the special series of jacks; these long butts being designated in solid black in Figure 17 of the drawings, and the special jack series being designated at X and Y in Figure 17. The slideable jack cams have 45 springs 60^a which normally urge the sloping heads thereof into the path of movement of the long butts of the jacks of special series X and Y during cylinder rotation.

In each of the series X and Y the central 50 jack 31^a is provided with an upper long butt 44. At each side thereof the jacks 31^b are provided with long butts 45 at the next lower butt level. Adjacent each of the butt jacks 31^b are jacks 31^c which have long butts 46 at the next lower 55 butt level. Adjacent each of the butt jacks 31^c are jacks 31^d which have long butts 47 at the next lower level, and the outermost jacks 31^e of each series X and Y are provided with long butts 48 at the next lower level. The cams 53, 54, 55, 56, and 57 are respectively in position to 60 actuate the butts 44 to 48 inclusive. The cams 58, 59, and 60 are respectively in position to actuate the jacks having butts 44, 45, and 46, as can readily be understood from Figure 17 of 65 the drawings.

The jack actuating means G furthermore includes a pattern control drum 61, shown in Figure 13 of the drawings, rotatably mounted upon the machine frame at 62 in any approved manner. This drum has a plurality of lugs on the periphery thereof intended to actuate a system of levers for selective control of the various cams 53 to 60 inclusive. The drum 61 is actuated in a step-by-step motion off the "104" gear of the 70 75 80 85 90 95 98

machine which is designated at 23 in Figure 13, and as has more specifically been described in my co-pending application, Serial No. 558,798, filed August 22, 1931. The lugs are detachably applied upon the drum 61 in any well known manner.

It will only be necessary to briefly describe the actuation of cams in the blocks 50 and 51 inasmuch as the actuating mechanism to be used is substantially the same as that described in my co-pending applications, Serial No. 586,- 635 and Serial No. 591,689, particularly with respect to the latter application. The drum 61 has a fixed ratchet wheel 64 provided with teeth 15 around the circumference thereof, preferably 60 in number. The "104" gear wheel 23 rotates once for every four revolutions of the cylinder C, and since it is intended to advance the drum 61 one tooth length for each two revolutions of the cylinder C, the gear wheel 23 is provided with diametrically opposed lugs 65 positioned to engage a pivoted lever 66, shown in Figure 13 of the drawings for actuating a pawl 69 upon the teeth 64 of the drum. A spring 70 maintains the lever 66 in position for step-by-step advancement of the drum.

Means is provided to cut out the pattern mechanism at desired intervals, which is accomplished by the mechanism more specifically described in the above identified co-pending applications through the throwing of the pawl actuating lever 66 out of the path of engagement with the lugs 65. This mechanism, which will not herein be further described, is generally designated at 72 in the drawings.

Referring to the yarn controlling device H, by means of which the plating or design providing yarns are wrapped upon predetermined needles, the same is entirely mounted upon the conventional latch ring R of the machine A, as is shown in Figures 1, 2, and 3 of the drawings, and elsewhere. This arrangement H includes a rotary bobbin stand 75 which consists of a central vertical shaft 76 having a bobbin shelf 77 keyed therewith at 78, and upon which a plurality of bobbins 79 are mounted in usual relation. The shaft 76 is provided with a sleeve 80 at the lower end thereof; said sleeve 80 at its upper end having an enlarged annular flange which is keyed at 81 (see Figure 2) to the shaft 76. The lower end of the shaft 76 is provided with an attaching block 82, shown best in Figure 19 of the drawings, to the bottom of which is detachably connected a disc 83, by bolts 84. This disc 83 slidably supports a pair of substantially opposed reciprocable yarn feed arms or members 90 and 91, and a second pair of similar yarn feed members 92 and 93 in parallelism with the first mentioned pair of said members. Generally, these yarn feed members receive the different colored yarns from the bobbin stand 75 and are cam actuated, in a manner to be subsequently described, in order to position the yarns upon predetermined selected needles of the needle set 55 as they are elevated by the means G.

The mounting of these slidable yarn feed arms is best shown in Figures 7 and 8 of the drawings. The disc 83 is provided with diametrically opposed pairs of grooves, as shown in Figure 8, wherein the horizontal slide portions of the members 90 to 93 inclusive are disposed and retained therein by means of detachable cover plates 95, at opposite sides of the disc attaching block 82.

A special frame is mounted on top of the latch ring R for rotatable support of the bobbin stand

and yarn feed arm mechanism, which consists of a hub 97, shown best in Figure 3 of the drawings, having radial arms 98 extending outwardly therefrom; the latter being releasably secured by posts 99 upon the latch ring R, so that said hub is spaced above the latch ring, as will be apparent from the drawings. The hub 97 has a depending detachable sleeve 101 secured therewith by means of bolts 102, as shown in Figure 3; the sleeve 101 providing additional bearing for rotatably receiving the sleeve 80 therein. The lower end of the sleeve 101 is provided with an annular cam supporting flange 105, which is adapted to support on the upper surface thereof a cam for actuating one pair of the yarn feed arms and on the lower surface a second cam for actuating the second pair of yarn feed arms.

An important feature of the invention is the simplicity of drive of the bobbin stand. The knitting machine is of the rotary cylinder type, and the bobbin stand and yarn feed guides are rotated at the same linear velocity as the cylinder. To that end the cylinder C is provided on the inner surface thereof at the top with a sleeve 110, fixed therein in any approved manner, which is provided with a short radially extending lug 111. The rotary yarn feed guide supporting disc 83 is provided with a depending finger 112, as shown in Figures 2 and 3 of the drawings, which, when the latch ring R is closed depends within the cylinder C in the path of rotation of the lug 111; the same engaging thereagainst to cause rotation of the bobbin stand and yarn feed guide supporting mechanism. The lug 111 and finger 112 are rounded and finished smooth in order to prevent injury to the fabric which is pulled downward into the cylinder by suitable take-up mechanism, between the lug 111 and finger 112. In practice it is found that this means of driving the bobbin stand direct from the cylinder will not injure or interfere with the finest of knitted fabrics.

Referring further to the yarn feed guides 90 to 93 inclusive, each of the same has a spring 114 normally drawing the guide radially inward into a retracted position with respect to the yarn feed upon the needles. Referring to Figures 15 and 16 a yarn feed guide projecting cam 115 is pivotally mounted at 116 upon the top of the flange 105 above described, which is normally spring retracted at 116, and which may be projected in a manner to be subsequently described, into the path of rotation of a horizontal arm portion 117 provided on each of the yarn feed guides 90 and 91 in order to forwardly project the yarn feed arms into needle wrapping position; Figure 16 showing the yarn feed guide 91 projected into this position by the cam 115. It is noted that the guides 92 and 93 do not have any portion which will engage the cam 115, so that in retracted or projected positions of the cam 115, there will be no actuation of the guides 92 and 93 thereby.

Referring to Figures 10 and 11 it will be noted that a cam 120 is pivoted at 121; this pivoting being upon the under-surface of the flange 105 (see Figure 3). The cam 120 is normally spring retracted at 122. The other set of yarn feed guides 92 and 93 are provided with extension portions 124 which lie in the path of the projected cam 120 and engage thereagainst to throw the yarn feed guides 92 and 93 into yarn needle wrapping relation; the projected position of the yarn feed guide 93 being shown in Figure 11 of the drawings.

It will of course be understood that any desired arrangement of slidable yarn feed guides

5

may be provided. In the example above described similar colored yarns are fed from two of the bobbins 79 to the needles through the yarn feed guides 90 and 91, and differently colored yarns 5 are fed from the other two bobbins 79 to the needles through the yarn guide members 92 and 93. With this arrangement clocking stripes or plated designs in two colors may be provided on the body of the hosiery being knitted, as is quite 10 apparent. It is of course within the contemplation of this invention that any number of yarn feed guides may be provided upon the rotary plating yarn control, for operation by each of the cams 115 and 120, in order to produce stripes 15 or designs throughout the circumference of the stocking. It is also within the scope of the invention to add at different levels other feed arms and operating cams to enable additional colored yarns to be knitted in with the other colored 20 yarns, so that a considerable number of contrastingly colored yarns may be produced in the stripe or plated design. Referring now to the means for throwing the cams 115 and 120 into and out of operation, a pair of vertical oscillating shafts 126 and 127 are provided, which bear 25 at their upper ends in a bracket 125 secured, as shown in Figure 9 of the drawings, on the arms 98 of the stationary portion of the bobbin stand construction; said shafts at their lower ends bearing 30 in the flange 105. At their lower ends the shafts 126 and 127 are respectively provided with lever arms 130 and 131, as shown in Figures 10, 11, 15, and 16 of the drawings, which actuate behind the cams 115 and 120 respectively, in order 35 to project said cams against their normal spring action when the yarn feed guides 90 to 93 inclusive are to be projected for yarn wrapping of the needles. At their upper ends above the bracket 125 the shafts 126 and 127 are provided with 40 radially extending arms 133 and 134 which through adjustable connecting rods 135 and 136 are connected to the upper ends of special levers 138 and 139. These levers 138 and 139 are pivoted on a shaft 140 which is secured in the carrier 45 ring offset 141 provided on the conventional knitting machine for receiving yarn feed levers. In fact, adjacent to the levers 138 and 139 a yarn feed lever 142 is pivoted at 143 for receiving the main knitting yarn 145, as shown in Figure 2, for 50 feed in usual knitting relation to the cylinder needles. Springs 150 are employed against the levers 138 and 139 to force them in such direction that the cam actuating levers 130 and 131 will normally lie inoperative as shown in Figures 55 10 and 15 of the drawings.

To selectively move the levers 130 and 131 into yarn feed guide cam projecting relation, a drum 151 is rotatably mounted at 152 upon a standard 60 153 of the knitting machine, which has keyed therewith a ratchet wheel 154. The drum 151 may be selectively provided with lugs 156 for actuating levers 158 and 159. These levers 158 and 159 pivot at 160 on the frame of the knitting machine, and through other levers 161 the levers 138 and 65 139 above described may be actuated.

Pattern control means regulates movement of the drum 151. This is of conventional construction and briefly includes a reciprocating pawl 165 having a pawl head actuating on the teeth of 70 the ratchet wheel 154; the lower end of the pawl 165 being pivoted, as shown in Figure 13, at 167, to an end of a cam actuated lever 168 which is pivoted at 169. The other end of the lever 168 is actuated by four cams provided upon a ring- 75 shaped cam 170 which is placed upon the con-

ventional "104" tooth gear of this type of knitting machine. Since four of these cams are provided on the ring 170 the pawl 165 will advance the ratchet wheel and drum 151 one tooth for each revolution of the knitting machine cylinder, as 5 the latter rotates four times for every revolution of the conventional "104" tooth gear.

Means is provided to normally maintain the pawl 165 inoperative until tripped by the pattern control mechanism. This means consists of a 10 pivoted pawl holder 175 shown in Figure 2 of the drawings, which thru a lever mechanism 176 is pivoted to an end of a lever 177, shown in Figure 13. The latter lever is spring actuated at 178 so that the end at the opposite side of the pivot 15 thereof from the lever arrangement 176 is normally pressed against the pattern control chain 180 in order that lugs 181 on the latter may rock the lever 177 and release the pawl holder. This pawl holder 175, as shown in Figure 2, normally 20 engages in a notch 182 at the upper end of the pawl 165 to hold the pawl end of the pawl in such position that it will not engage upon the teeth of the ratchet wheel for advancement, since in that position the lever 168 will be held out of 25 cam actuation. However, as soon as one of the lugs 181 of the pattern control chain 180 trips the lever 177, the pawl holder 175 will be thrown out of operation and the spring 183, shown in Figure 2, will draw the pawl 165 upwardly into such 30 position that a cam on the ring 170 may actuate against the lever 168 and pull the pawl 165 downwardly for advancing the ratchet wheel 154, in a manner which is perfectly apparent. After this advancement the pawl holder 175 snaps into the 35 notch 182 and holds the pawl 165 inoperative until another lug 181 on the pattern chain trips the same. Of course any desired number of lugs 181 may be provided, depending upon the number of 40 yarn changes desired in the stripe or plated design being knitted.

The yarns for producing the stripe or plate designs are assisted in being wrapped upon the needles in a manner quite similar to that set forth in my application Serial No. 591,689. That is, as 45 shown in Figures 5, 9, and 17 of the drawings, and elsewhere, a guide wire or member 190 is attached upon the carrier ring R of the machine, having a curved bar portion extending closely along the inside of the line of needles at a location just 50 below or about even the hook ends of the needles, when the latter are lowered, in order to prevent the plating yarns from becoming entangled with sinkers and other needles than those intended. Each series of yarn finger actuating cams, as 55 represented by the cams within the cam blocks 50 and 51 above described, is provided on the carrier ring R with a cooperative yarn guide bar or member 191 which is mounted upon a plunger 192 slidable in a bearing 193 on the latch ring 60 R, as shown in Figure 3 of the drawings. These yarn guide members 191 are provided with springs 194 normally tending to retract the said yarn guide members 191 to an inoperative position. The plunger portions 192 thereof are non-rotatable in the bearings 193 and maintained so by 65 means of radial projections 196 sliding in guide slots provided in the ends of the bearings 193, as shown in various views of the drawings. Wires 194 prevent the pins from slipping out of their 70 slots.

The yarn guide wires 191 may be simultaneously operated by a lever mechanism actuated off a pattern control drum or the like. A preferred arrangement is to provide a bell crank lever 200 75

5 pivoted at 200^a upon the frame of the knitting machine. It has a segment 201^a at the upper end thereof, which as shown in Figure 9 of the drawings slidably bears against the head ends 10 of the plungers of the yarn guide wires 191. Upon upward movement of the lever 200 the 15 yarn guide wires 191 will be fed inwardly across the tops of the central line of knitting needles into position for catching thereon any of the 20 plated yarns which may be projected into proper position by the yarn feed guides 90 to 93 inclusive, for wrapping the yarn thereof upon the predetermined needle which may be elevated, as will 25 be subsequently described.

15 The jack actuated cams mounted in the blocks 20 50 and 51 are operated in substantially the same manner as described in my co-pending applications above referred to, off the drum 61. That is, a number of levers 205 are pivoted at 206, as 25 shown in Figure 13 of the drawings. One end of each of these levers is actuated by the drum 61 by means of lugs arranged in predetermined manner upon the drum 61, as shown in Figure 14 for knitting the pattern shown in Figure 18; the 30 opposite ends of the said levers 205 being connected by suitable rods 207 to bell crank levers 208 which are pivotally mounted in suitable brackets 209 secured upon the frame of the machine; the said bell crank levers 208 actuating against suitable pins upon the jack actuating cams mounted in the blocks 50 and 51 shown in Figure 6 of the drawings. The spring 60^a normally urge the said cams into butt actuating position with the jacks of the set F, and the lugs upon the drum 61 actuate the levers 205 and thru the rods 207 and levers 208 springs are permitted to move the cams into such butt actuating relation, as can readily be understood.

35 Two typical set-ups shown in Figures 17 and 40 20 are adapted to be used in knitting the plated designs shown in Figures 18 and 21 respectively.

45 Referring to the set-up shown in Figure 17 for knitting the type of fabric L shown in Figure 18, the set of jacks F are provided with special series X and Y as above described, which are so manipulated by the cams 53 to 60 inclusive as to incorporate two distinctly different colored yarns within a single plated design, knitting "color within color", as such arrangement is referred to in the 50 art. In the fabric L the body yarn has a diamond-shaped design plated therein, using the wrap needle method, with an additional yarn of other color knitted therein. Thus, the diamond-shaped border of the design is a green yarn, and the 55 yarn interknitted within this border is a blue yarn. Additional colored yarns may be knitted into the design in the same courses with the other colored yarns by providing other yarn feeds and actuating cams upon the rotary bobbin stand, as 60 can readily be understood.

65 In the cam block 50 the five cams 53 to 57 inclusive are disposed so as to actuate respectively the jacks having butts 44 to 48 inclusive, in order to elevate the respective needles thereabove for taking the green plating yarns 215. The green 70 plating yarns are fed from the bobbins 79; it being understood that the bobbin stand is provided with a bobbin for each of the yarn feed guides 90 to 93 inclusive. In the particular pattern two bobbins of green yarn are provided and two bobbins of blue yarn, Figure 3 shows the bobbins with the green and blue yarns extended downwardly thru the sleeve 80 of the stand and 75 slidably through ducts provided radially through

the rotary base 83 and thence upwardly through slack yarn take-up devices 217, mounted on top of each of the yarn feed guides 90 to 93 inclusive; the yarns being continued downwardly, as shown in Figure 3 in position to be wrapped about 5 needles 32 as the latter are elevated by the cams in the block 50 or 51, when the yarn feed guide is projected, as is shown in Figure 3 of the drawings. The green yarns are of course threaded through the yarn feed guides 90 and 91, and the 10 blue yarns are similarly arranged and fed to the needles through the yarn feed guides 92 and 93.

15 In the sequence of knitting the design of the fabric L, the lug arrangement which is used on the drum 61 is shown in Figure 14 of the drawings. The cam 53 will first be thrown into butt elevating position by the dropping of the lever 205 through which the cam 53 is controlled into a notch 225 on the drum, which engages only the jacks 31 having butts 44 at that level, elevating 20 them. Previously the yarn feed arm projecting cam 115 shown in Figure 16 had been thrown out through the actuating mechanism above described. As shown in Figure 17 the yarn feed guides 90 and 92 are respectively provided with 25 green and blue yarns for feed to the needles above the special series of jacks X, and the yarn feed guides 91 and 93 feed their respective yarns to the needles above the special series of jacks Y. The cam 115 shown in Figure 17 will therefore 30 project the yarn feed guides 90 and 91 so that the green yarns will be caught upon the wire 191 immediately in advance of the elevation of the needles below the jack 31 having the special butt 44, so that the needle will have the green yarn 35 wrapped thereon before the yarn slips off the wire 191 as the cylinder and bobbin stand continue their rotation. In the fabric L this produces the plating stitches 230. Thereafter the cam 54 is thrown into jack actuating position by 40 dropping of its lever mechanism into the notch 226 shown in Figure 14 of the drawings, which elevates the two needles having jacks with the butts 45 of each of the series X and Y for taking the green yarns in the manner above described 45 and knitting of stitches 231 shown in the fabric L of Figure 18. During the knitting of these four courses wherein the stitches 230 and 231 appear the cam 115 remains thrown into yarn feed guide actuating position. Thereafter both of the yarn 50 feed guide actuating cams 115 and 120 are thrown into yarn feed guide actuating position as shown in Figures 16 and 11. Thereafter the cams 55, 56, and 57 are successively thrown into jack actuating position by the respective dropping of 55 their lever mechanisms into the spaces 226^a, 227, and 228 for the knitting of the plating stitches 232, 233, and 234 out of the green yarns. Simultaneous with the respective throwing of the cams 55, 56, and 57 into jack elevating position the 60 cams 58, 59, and 60 are thrown into jack elevating position for elevating the jacks of the special series X and Y having butts 44, 45, and 46 respectively, in order to knit in the fabric L the stitches 235, 236, and 237, which respectively appear in the same courses of the fabric L as the green yarn stitches 232, 233, and 234. The stitches 235, 236, and 237 are of course of the blue yarn and the needles elevated by the cams 58, 59, and 60 take the blue yarn from the yarn feed guides 70 92 and 93 which are actuated by the cam 120, as can readily be gained from Figure 17 of the drawings. These cams 58, 59, and 60 are actuated to produce the stitches 235, 236, and 237 by dropping of their respective lever mechanisms 75

into the lug spaces 229, 229^a, and 229^b. As has been described in my co-pending application, Serial No. 591,689, a needle and jack lowering cam 240^a is provided to lower the needles and jacks 5 which have been elevated by any of the cams 53 to 57 inclusive after the needles actuated thereby have taken the green yarn, at a time prior to elevation of any of the needles by the cams 58, 59, and 60, so that there will be no interference 10 of the needles which take the green yarn, with the blue yarn. This cam 240^a is of course very important in that it directly permits the knitting of "color within color" in a plated design. There- 15 after the stitches 238 and 239 of the blue plating yarn 240 are knitted upon the needles actuated by the cams 59 and 58 respectively, whose lever mechanisms are actuated off the drum spaces 241 and 242, shown in Figure 14. The green plated portion of the design is completed as to 20 the stitches 245, 246, 247, and 248, by successive operation of the cams 56, 55, 54, and 53, whose respective lever mechanisms are successively actuated off the pattern control drum spaces 250, 251, 252, and 253. Of course, the cam lugs on the 25 pattern striping drum 151 may be such as to maintain both the yarn feed guide actuating cams 115 and 120 in yarn projecting relation at all times, for the particular design shown in the fabric L, although there are instances in the knitting 30 of plated designs using "color within color", when one of the cams 115 or 120 should be in inoperative position. That arrangement of parts is shown in Figure 2 of the drawings.

It is quite apparent that a greater or less number 35 of jack elevating cams may be employed in either of the cam blocks 50 or 51, depending upon the plated design or striping which it is desired will appear in the fabric, and many and varied 40 complicated patterns, designs, stripes, and contrasting yarn figures may be knitted in plated relation after the wrap needle method with the improved machine of this invention.

Figure 20 shows a somewhat modified arrangement 45 for knitting of plated designs and pattern effects, although this arrangement will not permit of knitting one colored yarn in contrasting effect within a plated design of another color, in the same courses of knitting. The striped and pattern effects may be secured by utilizing contrastingly colored yarns, but the said yarns are 50 not knitted together in the same course. Thus in Figure 21 the two diamond designs indicated at 255 are knitted with a green plating yarn and the other striped and design plated portions 256 55 are knitted with the blue plating yarn. The arrangement shown in Figure 20 contemplates only one cam block having a plurality of cams 257 therein of any desired number, which are five 60 in number in the example shown, but which may be a greater or less number depending upon the number of needles which it is desired to include in the special jack series. In this arrangement the projecting cams 115 and 120 are located one 65 above the other on the rotary bobbin stand so that they will project the yarn feed guides for the contrasting green and blue plating yarns at the same location, but not at the same time, since only one or the other of the cams 115 and 70 120 is in yarn feed guide projecting relation at any one time, as can readily be understood. This permits of a simpler arrangement inasmuch as it is not necessary to employ a plurality of jack actuating cam blocks and the attendant cam lever actuating mechanism.

As will be noted from Figure 1 of the drawings the cam 240^a above described is actuated off a bell crank lever 260 connected to a lever mechanism 261 which is actuated off the usual pattern control drum 262. The connecting rod 201 shown 5 in Figures 1 and 6 of the drawings is connected with this rod 261 so as to throw the plating yarn restraining wires 191 into position at the same time that the cam 240^a is thrown into position. If desired these wires 191 may be operated off 10 the pattern control drum independent of the cam 240^a, as may be required when knitting some special plated patterns.

A very important feature of the invention is 15 the fact that there will be no necessity for re-setting parts of the machine and particularly the plating arrangement in event it becomes necessary to lift the carrier or latch ring, since the entire stationary and rotary parts of the bobbin stand and plating yarn control mechanism are 20 mounted so as to facilitate the usual lifting and lowering operations of the said latch ring without other operations.

Another important feature of the invention is 25 the yarn slack take-up mechanism mounted directly upon the rotary yarn feed arms.

The usual set of needle actuated cams is provided, including the stitch cams 265. The body 30 yarn 145 may be fed to the needles by one or more of the conventional yarn guides 142; the yarns being knitted in the fabric at the knitting point 267. The cams and parts shown in the drawings which are not described are conventional.

Various changes in the shape, size, and arrangement of parts may be made to the forms of invention herein shown and described, without departing from the spirit of the invention or the scope of the claims.

I claim:

1. In a knitting machine the combination of a rotary needle supporting cylinder, a rotary bobbin stand, yarns upon the bobbin stand, independently movable feed members rotatable with the bobbin stand, means to selectively move said members into yarn feed relation with the needles of the cylinder, and means movable with and directly on each of said members for taking up slack yarn at the feeding end of the said yarn.

2. In a yarn feeding device for knitting machines the combination of a support, a rotary bobbin stand mounted upon the support, a reciprocating radially movable yarn feed member, cam means for projecting the member in yarn feeding relation, and a slack yarn take-up directly 55 mounted on the member for taking up slack yarn at the feed end thereof.

3. In a knitting machine the combination of a set of independently movable needles, means to feed a body yarn thereto to knit fabric, means to manipulate separate needles of a certain group of needles to receive a wrapping thread with floats of the wrapped thread extending across the back of the intermediate needles, means to feed upon some or all of the needles of the same group which did not receive the first wrapping thread and in the same knitted courses therewith a second wrapping thread with floats extending across the back of any intermediate needles, said 70 wrap yarn feeding means comprising reciprocably slideable yarn carriers, and selective means for independently moving the same into and out of yarn feeding relation with the needle manipulating means.

4. In a knitting machine the combination of a set of independently movable needles, means to feed a body yarn thereto to knit fabric, means to manipulate separate needles of a certain group of needles to receive a wrap thread with floats of the wrap thread extending across the back of intermediate needles, means to manipulate other needles of the said group which did not receive the first wrap thread for receiving a second wrap thread with floats thereof extending across the back of any intermediate needles, restraining members coating with the last two mentioned means movably mounted for movement into and out of yarn receiving relation with their respective wrap threads, and pattern control means for actuating said restraining members in a cooperative relation with the needle elevation.
5. In a knitting machine the combination of a cylinder having independently movable needles therein, a rotary bobbin and yarn feed support including yarn feed members and means to move them into position for feeding yarn upon predetermined elevated needles, means to selectively elevate the needles in such predetermined relation for receiving the yarns from said feed members, and a yarn restraining device cooperating with the said feed members in restraining yarn for the application thereof upon the selected elevated needles, said yarn restraining device being movable to a position inside of the line of needles to restrain the yarn as fed by the yarn feed members, means normally retracting the yarn restraining device to a non-interfering relation with needle elevation to a position outside of the needle line, and pattern controlled means for moving the yarn restraining member into its effective yarn restraining relation with respect to the yarn fed by said feed members.
6. In a knitting machine, the combination of a rotary needle cylinder, an independent needle set therefor, means to selectively elevate the

needles in the set, a wrap yarn feed member movable above the needle line into yarn feeding relation with respect to elevated needles, a movable yarn restraining member for holding the wrap yarn in position so that only the needle or needles elevated by the first mentioned means receive the wrap yarn thereon, and pattern controlled means for moving said yarn restraining member into and out of yarn receiving and restraining relation.

7. In a circular knitting machine the combination of a set of independent needles, means for raising the needles selectively for wrapping, selective means for feeding wrapping yarns to the needles, a wrap yarn restraining member movable into wrap yarn restraining relation with those wrap yarns applied to the needles by said selective feeding means for holding a wrap yarn or yarns in position for disposal upon only the needle or needles raised by said means first mentioned, and pattern controlling means for moving said yarn restraining member into or out of yarn restraining position.

8. In a circular knitting machine the combination of a set of independent needles, means for raising the needles selectively at a plurality of points, means for lowering the needles at a location intermediate said points, selective means for feeding wrap yarns to the needles at each of said points, wrap yarn restraining members at each of said points movable into wrap yarn restraining relation with those wrap yarns applied to the needles by said selective feeding means for holding the respective wrap yarn or yarns in position for disposal only upon the needle or needles raised by the means first mentioned at each of said points, and pattern controlling means for simultaneously moving said restraining members into or out of wrap yarn restraining position.

40 HARRY McADAMS.
